[54] LAMP WITH CONICAL SHADE

Attorney, Agent, or Firm—Jack Lo

[75] Inventor: **Orlando Diaz-Azcuy**, San Francisco, Calif.

[57] CLAIM

[73] Assignee: **Boyd Lighting Company**, San Francisco, Calif.

The ornamental design for a lamp with conical shade, as shown and described.

[**] Term: 14 Years

DESCRIPTION

[21] Appl. No.: 29/096,732

FIG. 1 is a front perspective view of a lamp with conical shade showing my new design.

[22] Filed: Nov. 19, 1998

FIG. 2 is a front view thereof; the rear, right, and left side views are identical.

[51] LOC (6) Cl. 26-05

FIG. 3 is a top view thereof.

[52] U.S. Cl. D26/110

FIG. 4 is a bottom view thereof.

[58] Field of Search D26/93, 102-112; 362/410-414, 806

FIG. 5 is a front perspective view of an alternative embodiment of my new design.

[56] References Cited

FIG. 6 is a front view of the alternative embodiment; the rear, right, and left side views are identical.

U.S. PATENT DOCUMENTS

FIG. 7 is a top view of the alternative embodiment; and,

D. 328,153 7/1992 Benghozi D26/110

FIG. 8 is a bottom view of the alternative embodiment.
